CLAIM

The ornamental design for a child's toilet trainer, as shown and described.

DESCRIPTION

FIG. 1 is a perspective view of a child's toilet trainer showing our new design;

FIG. 2 is a top plan view thereof;

FIG. 3 is a front elevational view thereof;

FIG. 4 is a left side elevational view thereof, the right side being a mirror image of the left side;

FIG. 5 is a rear elevational view thereof; and,

FIG. 6 is a bottom plan view thereof.

FIG. 1.

FIG. 2.

FIG. 6.

FIG. 4.

FIG. 3.

FIG. 5.
